UNITED STATES PATENT OFFICE.

JULES A. LE BLANC, OF PORT ARTHUR, TEXAS.

PACKING RING.

Application filed March 20, 1924. Serial No. 700,738.

To all whom it may concern:

Be it known that I, JULES A. LE BLANC, a citizen of the United States, residing at Port Arthur, in the county of Jefferson and State of Texas, have invented certain new and useful Improvements in Packing Rings, of which the following is a specification.

This invention relates to new and useful improvements in packing rings which are especially adapted for use in pumps or the like wherein gasoline or kerosene or any other liquid is used, and further adapted to be used on packing rods.

One of the important objects of the invention is to provide a packing ring which is formed of tupelo root. This tree from which the packing ring is formed grows in the swamps and low lands of North America, and the wood taken from these trees when in use as a packing ring will not absorb the liquid as is the case with the other wooden or fibrous packing rings now in use.

A further object of the invention is to provide a packing ring of the above mentioned character, wherein the same is provided with a casing which extends entirely around the ring the outer wall of the casing being of a greater thickness than the other walls thereof.

30 A further object of the invention is to provide a packing ring of the above mentioned character, which is simple in construction, inexpensive, strong and durable and further well adapted for the purposes for which it is designated.

Other objects and advantages of this invention will become apparent during the course of the following description.

In the accompanying drawing forming a part of this specification and in which like numerals designate like parts throughout the same,

Figure 1 is a plan view of the packing ring embedded in the casing,

45 Figure 2 is a side elevation thereof partly in section,

Figure 3 is a top plan view of a packing ring formed of tupelo root without having a casing extending therearound,

50 Figure 4 is a vertical section therethrough, and

Figure 5 is a fragmentary detail view of a modification showing the manner in which the packing ring is split.

55 In the drawing wherein for the purpose of illustration is shown the preferred em-

bodiment of my invention, the numeral 1 designates a packing ring which is made from tupelo root which is obtained from the trees growing in the swamps and low 60 lands of North America. The packing ring is substantially rectangular in cross section as clearly shown in Figure 2 of the drawing, and adapted to extend entirely around the packing ring is the casing 2 which may be of any suitable material such as rubber, asbestos or the like, and I do not wish to limit myself to the particular kind of material to be used. As is further noted from Figure 2 of the drawing, the outer peripheral wall of the casing is of a thickness greater than the thickness of the other walls of the casing, and the purpose of this construction is to provide a packing casing which will be strong and durable. A packing ring of the above mentioned character is especially adapted for use upon packing rods on hot liquid pumps and will be very 70 efficient in its operation. By using a packing ring formed of wood such as the tupelo 75 root the same will not be subject to absorption and this will render the packing ring very efficient in its operation and will prolong the durability of the same.

In Figures 3 and 4 of the drawing, a packing ring formed of tupelo root is shown and is illustrated by the numeral 3, and the same is split as at 4. In using a packing ring of the character shown in Figures 3 and 4 of the drawing, the use of a casing therefor is 80 not necessary and a packing ring of this type is especially adapted for use in packing the fluid end of a pump for use in pumping hot liquids such as gasoline or kerosene. This packing ring is also substantially rectangular in cross section as is illustrated at 85 5 in the drawing.

In Figure 5 of the drawing the packing ring is divided or split on a bias as is illustrated at 6 and this construction permits 100 the cutting away of the respective ends of the split ring to the proper size. Any suitable means may be provided for reducing the size of the packing ring such as by employing a sharp knife, a file or the use of an 105 emery wheel, and I do not wish to limit myself to the particular manner in which the respective ends of the ring are cut away.

It will thus be seen from the foregoing description, that a packing ring has been 110 provided which is very economical and is constructed of such material as to be strong

and durable and will resist absorption of the liquids in which the packing ring is supported or operates and furthermore, by using tupelo root a packing ring is provided
5 which is very light in weight.

While I have shown the preferred embodiment of my invention, it is to be understood that various changes in the size, shape and arrangement of parts may be resorted to
10 without departing from the spirit of the

invention and the scope of the appended claim.

Having thus described my invention, what I claim is:—

A packing ring structure including as an ¹⁵ element an annular ring formed from the wood of tupelo root.

In testimony whereof I affix my signature.

JULES A. LE BLANC.
